PHILIPP MOELLENDICK, OF NEW YORK, N. Y.

GAS-STOVE ATTACHMENT.

1,142,603.

Specification of Letters Patent. Patented June 8, 1915.

Application filed December 23, 1914. Serial No. 878,642.

To all whom it may concern:

Be it known that I, PHILIPP MOELLENDICK, a subject of the Emperor of Germany, residing in the borough of Manhattan, city, county, and State of New York, have invented an Improvement in Gas-Stove Attachments, of which the following is a specification.

My present invention relates to that type 10 of gas stove attachments adapted to determine the limitations of the flame from the gas burner, and to confine and direct the heat from the same to the pot or pan, or other vessel, to which it is desired to apply it. 15 In carrying out my invention, I preferably employ a tapered body member extending between the top or platform of the stove and the burner thereof, the walls of the body member being so inclined as to permit the 20 heated air within the chamber, inclosing the same, to expand and to be directed upwardly against the bottom of a vessel placed above the aperture. I also provide a lid or cover, adapted to fit within a portion of the top 25 of the range, immediately above the burner, and the upper end of the body member of the attachment, and provided centrally with an opening through which the heat may escape downwardly against the central portion 30 of a vessel, and furthermore, in instances where it is desirable to concentrate substantially the entire heat to the bottom central portion of a vessel, I provide an auxiliary and removable deflector, placed 35 within the body member of the attachment with the walls tapered in the opposite direction so as to direct the heat and the flames to the desired point, all of which will be hereinafter more particularly described. 40 In the drawing, Figure 1 is a plan of my improved gas stove attachment, and Fig. 2 is a central transverse section of the same showing a portion of the gas burner.

In the drawing, 10, indicates the body portion 45 of my improved gas stove attachment or gas saver. This is made of metal or other suitable material, and at its upper or outer end is suitably connected to the top 12 of the gas range. This may be made, as illustrated, 50 of any suitable design. At its lower end, the body portion 10 rests upon and extends over a gas burner 11, which may be of the form illustrated or of any well known type.

The top of the stove is provided, in suitable 55 positions, with ribs 13, adapted to sup-

port a pot, pan, or other vessel, in a position appreciably spaced apart from the major portion of the top of the stove, and the body portion 10 of the attachment is preferably conical with the inner faces appreciably 60 concave, so as to permit the air and gases within the attachment to expand and to be properly directed to the desired points.

The parts forming the top of the stove adjacent their attachment to the body portion 65 10, are recessed as indicated at 15, to receive a lid or cover 16, which may be placed within these recesses and supported by a part of the top of the stove, so that when in position, the surfaces of the lid within the same 70 are on substantially the same plane as the major portion of the top of the stove. This lid may be provided with a lifter opening 17, and is centrally provided with an opening and series of radially placed projections 75 19, with intervening recesses 18, the former to retain the heat from the burner and the latter to permit the escape of the heated gases therefrom. Also within the body member 10, in suitable positions, there are 80 lugs 21, adapted to support a deflector 20. This deflector is also preferably conical, and when in position the walls thereof taper in the direction opposite to that of the walls of the body member 10. At its upper or 85 outer end, the deflector 20 is also provided with a series of radially placed projections 22, with intervening recesses 23, and as shown in Fig. 1 the projections and recesses 90 in the lid or cover may be placed in a staggered relationship in regard to the projections and recesses in the deflector 20, to cause a more even distribution of the heat from the burner.

It will be apparent that there are appreciable spaces 24 between the upper or outer ends of the body portion 10, and the adjacent surface of the lid or cover 16. These permit of the escape of the heated gases from the burner, after the same have been 100 utilized.

It will be apparent that, depending upon the nature or character of the work to be done, the lid or cover, or the deflector or both these members, may be dispensed with. When using the attachment with the cover and without the deflector, the heated gases are distributed and retained within the confines of the body member, and the lid, being directed for the greater part through an

opening in the lid against the central portion of the vessel being employed, a relatively small part only passing through the apertures 24. When the deflector, as well as the lid, is employed, substantially all the heated gases are directed immediately through the central portion of the vessel employed, and this is the case, irrespective of whether or not the lid or cover is used simultaneously with the deflector. When both are used together, and the projections and intervening recesses placed in a staggered relationship, distribution of the heated gases will be more even and the intensity of the same greater.

I claim as my invention—

1. A gas stove attachment comprising a conical body member, secured to and depending from the top of the gas stove and extending between the same and a gas burner therein, a lid supported upon the top of the gas stove in a position immediately above but spaced apart from the outer end of the said body member, and a deflector

within the said body member with the walls thereof inclined in the opposite direction. 25

2. A gas stove attachment comprising a conical body member secured at its outer end to the top of a gas stove and extending between the same and a gas burner thereof, 30 a central apertured lid having a series of radially placed lugs and intervening recesses set in the top of the gas stove immediately above and in a position spaced apart from the outer end of the said conical body member, and a deflector having in its outer end a series of radially placed lugs with intervening recesses placed within the said conical body member in such a position that the lugs and recesses thereof are in a staggered 35 relationship to the lugs and recesses in the lid. 40

Signed by me this 18th day of December, 1914.

PHILIPP MOELLENDICK.
